DESIGN FOR A TOY PISTOL

James P. Robinson, Paterson, N. J., assignor to
Plastic Art Toy Corporation of America,
Rutherford, N. J., a corporation of New Jersey

Application October 24, 1946, Serial No. 134,215

Term of patent 7 years

(Cl. D34—15)

To all whom it may concern:

Be it known that I, James P. Robinson, a citizen of the United States and resident of Paterson, in the county of Passaic and State of New Jersey, have invented a new, original, and ornamental Design for a Toy Pistol, of which the following is a specification, reference being had to the accompanying drawing, forming a part thereof, and of which Fig. 1 is a view in side elevation of a toy pistol showing my new design; Fig. 2 is an end elevation thereof; Fig. 3 is a view in elevation of the other end thereof; Fig. 4 is a

bottom plan view thereof; and Fig. 5 is a sectional view on line 5—5 of Fig. 1.

I claim:

The ornamental design for a toy pistol, substantially as shown.

JAMES P. ROBINSON.
